ADJUSTABLE KEY

Carlos Jaramillo Borda, Bogota, Colombia

Application July 13, 1951, Serial No. 236,568

1 Claim. (Cl. 70—411)

1

The present invention relates to an adjustable key for use with locks of the type in which the paths of movement of the tumblers are parallel to the axis of the plug of the lock. A lock of this general type and a key suitable for use with such locks are illustrated and described in my prior Patent No. 2,473,273 of June 14, 1949.

The present invention is an improvement over the adjustable key shown in the patent above mentioned. An object of the present invention is to provide a key which is more sturdy, economical and simple than the key of my prior patent. A further object of the invention is to provide a key having a wider range of adjustments.

An understanding of the invention may be had by reference to the accompanying drawings, wherein

Figure 1 is a front elevational view of a lock with which the key is intended to be used;

Figure 2 is a longitudinal sectional view through a lock and key, and showing the key about to be inserted into the lock;

Figure 3 is a view similar to Figure 2, showing the relative positions of the elements of the lock and key after insertion of the key into the lock;

Figure 4 is a perspective view of the key in condition for use;

Figure 5 is a perspective view of the key in position for adjustment;

Figure 6 is a transverse sectional view taken in the direction of the arrows along the line 6—6 of Figure 4, and;

Figure 7 is a longitudinal sectional view taken in the direction of the arrows along the line 7—7 of Figure 6.

The lock is illustrated as incorporated in a member 11 which may be a door, the front of a desk drawer, or any other appropriate member which it is desired to lock in a particular position. The lock includes a generally cup-shaped housing 12 which is recessed into the member 11. The plug of the lock is designated by the numeral 13, and this plug is rotatable within the housing 12 when certain tumblers hereinafter described are in appropriate positions. The plug 13 is provided with a stem 14 which carries at one end a cam or lever 15 which controls the bolt of any appropriate locking mechanism, not shown. An annular ring 16 is secured to the housing 12 and to the member 11 by means of screws 17. The inner edge of the annular ring 16 overlies the periphery of the plug 13 to prevent removal of the plug from the lock.

The plug 13 is illustrated in Figure 2 as occupying a position which causes the lever or cam 15

5 to be in locking position. The plug 13 is prevented from rotating from this position by tumblers which are movable in paths which are parallel to the axis of the plug. The lock is illustrated as provided with six tumblers, although a greater or lesser number of tumblers may be employed. These tumblers are preferably of different lengths. For example, the tumbler 18 shown in Figure 2 is illustrated as considerably longer than the tumbler 19. The tumblers 18 and 19, as well as the other tumblers, are backed by compression springs 20 which are positioned in wells 21 in the housing 12. The inner ends of springs 20 abut the ends of screw plugs 21a which are threaded into the housing 12. The screw plugs 21a are readily removable to facilitate interchange of tumblers. The outer ends of the tumblers 18 and 19 abut against the enlarged inner ends 22 and 23 of thrust members 24 and 25, respectively. The combined length of the tumbler 18 and the enlarged portion 22 of the thrust member 24 is equal to the combined length of the tumbler 19 and the enlarged portion 23 of the thrust member 25.

10 The plug 13 can be rotated to release or retract the bolt of the lock only while the tumblers 18 and 19 are in the positions illustrated in Figure 3. It will be apparent from an inspection of Figure 3 that the tumbler 18 has been depressed by the thrust member 24 to such an extent that the tumbler lies entirely within its well 21. It will also be seen that the tumbler 19 has been depressed by means of the thrust member 25 to such an extent that this tumbler lies entirely within its well 21. It will be seen, however, that the tumbler 18 15 has been depressed to a much greater extent than the tumbler 19.

20 The foregoing brief description is sufficient to explain the manner of operation of the lock. I have described the movements of only two of the tumblers, but it will be understood that the other tumblers embodied in the lock are operated in a similar manner. It is preferable that no two of the tumblers in any lock be of the same length, thus making it necessary to move the thrust members corresponding to the members 24 and 25 by different amounts during opening of the lock.

25 The key is provided with a body member 26 having six longitudinally extending parallel passages 27 therein. The passages 27 may receive pins in the manner illustrated in Figure 2. The pin 28 is intended to cooperate with the thrust member 24 of the lock and the pin 29 is intended to cooperate with the thrust member 25. Since the thrust member 24 must be depressed by the

greater amount, the pin 28 is longer than the pin 29. The pins in the remaining four passages of the key will be of appropriate lengths to properly cooperate with their respective thrust members.

All of the pins of the key are provided with similar heads 30, and these heads bear against the rearward end 31 of the body member 26. A handle member 32 is hinged to the body member at 33, and is provided with a suitable clasp 34 to retain the body member and handle member in operative relationship. The handle member 32 is provided with a plane surface 35 which is parallel to and spaced from the rearward end 31 of the body member 26. This surface 35 bears against the rearward ends of the heads 30 of the pins when the body and handle members are in the positions illustrated in Figures 4 and 7. The surface 35 is preferably provided with a rubber or rubber-like covering 36.

The body member is also provided with a central passage 37 which may be used to carry a spare pin or used to temporarily receive a pin during adjustment of the key. The body member 26 also is provided with a rectangular cavity 38 which is intended to cooperate with a rectangular projection 39 on the lock. The cavity 38 and the projection 39 assist in positioning the key relative to the lock and also serve to assist in transmitting from the key to the lock the force necessary to rotate the cylinder.

The handle member 32 may also be provided with a plurality of passages 40, which extend transversely therethrough. These passages are for the purpose of receiving and storing additional pins.

It will be apparent from the foregoing description that for any given lock or for any given combination of tumblers within the lock, the key must have pins of the proper lengths in the passages 27. Only one combination of pins will be operative to actuate the lock, and that combination of pins must be arranged properly in the passages of the key. The key can be opened for adjustment as illustrated in Figure 5 and it is a simple matter to "scramble" the pins so that they must be adjusted by one having the required information before the key can again be used to open the lock. It is possible to remove certain of the pins which have been in passages in the body member and to substitute pins which have been taken from the passages in the handle member. It may be helpful for the pins to be provided with numbers on their heads 30, and for the passages 27 to be provided with letters adjacent thereto on the surface 31. 55

The combination and arrangement of tumblers in the lock can be readily changed at frequent intervals to further reduce the possibility of unauthorized opening of the lock.

The illustrated form of the invention is to be regarded as exemplary only, and it will be apparent that various changes and modifications may be resorted to without departing from the broader aspects of the invention as defined by the following claim.

Having thus described my invention, I claim:

1. An adjustable key for use in locks of the type in which a plurality of tumblers extend parallel to the axis of the plug, said key comprising a body member defining a plurality of parallel passages extending from the forward end to the rearward end thereof, said passages being arranged for axial alignment with corresponding tumblers of the plug of the lock with which the key is to be used, the rearward end of said body member being a plane surface normal to said passages, a pin in each of said passages, the forward ends of said pins terminating within said passages, heads on the rearward ends of said pins bearing on the rearward end of said body member, a handle member, a hinge attaching said handle member to said body member, said handle member having a plane surface thereon which is normally disposed parallel to and spaced from the rearward end of said body member, said surface of said handle member engaging said heads of said pins and clamping the same against the rearward end of said body member, said handle member being swingable on said hinge to withdraw said surface of said handle member from engagement with the heads of said pins to permit removal of said pins from said passages, and releasable clasp means for retaining said handle member in position to clamp said heads of said pins against the rearward end of said body member.

CARLOS JARAMILLO BORDA.
